Patented June 26, 1962

193,127

CARRYING CASE FOR A BOWLING BALL OR SIMILAR ARTICLE

Paul Belokin, Jr., 6919 W. 43rd St., Berwyn, Ill.

Filed Dec. 22, 1961, Ser. No. 68,035

Term of patent 7 years

(Cl. D87—5)

FIGURE 1 is a front elevational view of a carrying case for a bowling ball or similar article embodying my design;

I claim:

The ornamental design for a carrying case for a bowling ball or similar article, as shown.
